UNITED STATES PATENT OFFICE.

JOHN F. DOOLITTLE, OF CLEVELAND, OHIO, ASSIGNOR TO THE CLEVELAND PUNCH AND SHEAR WORKS COMPANY, OF SAME PLACE.

BENDING-MACHINE.

SPECIFICATION forming part of Letters Patent No. 589,167, dated August 31, 1897.

Application filed May 25, 1896. Serial No. 592,910. (No model.)

To all whom it may concern:

Be it known that I, JOHN F. DOOLITTLE, a citizen of the United States, and a resident of Cleveland, county of Cuyahoga, and State of Ohio, have invented certain new and useful Improvements in Bending-Machines, of which the following is a specification, the principle of the invention being herein explained and the best mode in which I have contemplated applying that principle so as to distinguish it from other inventions.

The annexed drawings and the following description set forth in detail one mechanical form embodying the invention, such detail construction being but one of various mechanical forms in which the principle of the invention may be used.

The object of my invention is to devise in a bending-machine a roll which can be used in bending stock of varying thickness, eliminating thereby the necessity and inconvenience of changing rolls for each different thickness of stock; and a further object is to provide the machine with an adjustable guide which will perform its function with less frictional resistance than do the guides at present used in such machines.

To accomplish the first-named object, I construct my roll of two roll-sections, which are keyed and slide upon the same shaft, a space being left between the two sections, forming an annular slot, the width of the said slot being regulated by means of screw-bolts passing and threaded through the one section and engaging the face of the other section.

In order to reduce the frictional resistance occasioned by the contact of the stock with the guide, I provide the guide with a rotating face, the force of the contact being received by ball-bearings, as hereinafter described.

In the annexed drawings, Figure I is a perspective view of a bending-machine provided with my improved rolls and guides. Fig. II is a view, partly in vertical section and partly in elevation, of one of the improved rolls. Fig. III is an end elevation of one of my improved rolls. Fig. IV is an end elevation of the combination of the three rolls, showing their arrangement in the machine and also showing the number and position of the guides,

together with a piece of angle-iron in the course of the operation of the machine. Fig. V is a front elevation of the rolls, showing the position of the rolls and guides and the relation of the slots when set for bending flat stock. 55 Fig. VI is also a front elevation of the rolls and guides and shows the relation of the slots when set for bending angle-iron. Fig. VII is a view, partly in vertical section and partly in elevation, of my improved guide. Fig. 60 VIII is a view, partly in vertical section and partly in elevation, of the adjusting mechanism of the guide-rod.

The rolls A, B, and B' are driven in the direction indicated by the arrows by the well-known means of the pulleys and gears shown in Fig. I, the upper roll A having vertical adjustment by means of pulleys E and E', worms C, wheels D, and screws F in the usual manner.

The guide-rod g of the guide G extends 70 through the housings H and H', sliding easily through housing H and having its adjusting mechanism at the housing H', as hereinafter described.

The shaft J is turned down at its end, forming thereby the shoulder j, against which the roll-section a of the roll is backed and keyed to the shaft by means of feather j'. The roll-section a', having the three screw-bolts M passing therethrough and parallel to the shaft 80 J and having screw-threaded engagement therewith, is also mounted and keyed to the said shaft in the same manner.

The end of the shaft is turned down and threaded to receive the loose washer K and 85 the nut L.

The variation in the width of the groove can be effected by turning the screw-bolts M after loosening up the nut L.

The guide G is composed of the guide-rod 90 g, extending, as before stated, through both housings H and H', and is enlarged to a suitable diameter at the guide end, as shown in Fig. VII. The inner or primary face g⁴ is constructed of a hardened-steel disk and is 95 formed with a ball-race g⁷ around and near the edge of its face. The outer or secondary face g⁸ is also constructed of a hardened-steel disk and has a similar ball-race g⁷, formed as in the primary face g⁴, and is further pivoted 100

to the guide-rod g by means of the screw g^2 , about which the disk g' freely rotates. A jam-block g^6 is jammed down upon the threads of the screw g^2 by means of the set-screw g^5 to prevent it from backing out. Balls g^3 are placed in the races and form the bearing for thrusts on the disk g^4 in the direction of its axis.

The opposite end of the guide-rod has 10 threaded engagement with the thimble h , which has rotating bearing in the housing H' and, being formed with the flange h^4 , limits the lateral movement of the guide-rod toward the housing H' . A washer h' is keyed 15 upon the opposite side of the housing H' and is provided with holes h^3 in its periphery for receiving a bar, by means of which the thimble is turned, thus laterally adjusting the guide-rod and its attached guide. Two such 20 guides are provided in the machine, as shown in Fig. IV, so that the machine may be reversed and the stock sent in the other direction.

Rolls may be similarly constructed having 25 more than two sections, so that such stock as channel-bars and I-beams may be bent, the number of sections and position of the slots depending upon the form of the stock.

When flat iron is bent, a washer N of the 30 required thickness is inserted between the sections of the roll and a washer N' inserted between the shoulder j and the inner section a' , Fig. V.

In bending bars of irregular or unsymmetrical cross-section, such bars, by virtue of the 35 inequality of the internal strains produced in the bending operation, have a tendency to warp on issuing from the rolls, and would so warp were not the guide G provided for such 40 a contingency.

The direction in which the bars will warp may be usually determined by the form of the cross-section, but if such cross-section does not give the necessary data for such 45 determination the direction of warp may be determined empirically. In either case, when said direction is known the bars are so fed into the rolls that the warping tendency will always be toward the guide, which receives 50 the consequent thrust and performs the operation of equilibrating the internal inequalities, so that the ring remains flat on completion.

Other modes of applying the principle of 55 my invention may be used for the mode herein explained. Change may therefore be made as regards the mechanism thus disclosed, provided the principles of construction set forth respectively in the following claims are 60 employed.

I therefore particularly point out and distinctly claim as my invention—

1. In a bending-machine, a roll consisting 65 of the combination with two elemental roll-sections, of a shaft adapted to mount said roll at its end, and provided with means

adapted to limit one of said sections in its motion in the direction of the axis of said shaft, the other section provided with means adapted to vary the distance between said 70 two sections, said shaft provided with means for limiting the action of said varying means, whereby said two sections are fixed relatively to each other, substantially as set forth.

2. In a bending-machine, a roll consisting 75 of the combination with two elemental roll-sections, of a shaft adapted to mount said roll at its end and provided with means adapted to limit one of said sections in its motion in the direction of the axis of said 80 shaft, the other section provided with screw-bolts passing longitudinally therethrough, having screw-threaded engagement therewith and adapted to vary the distance between said two sections, said shaft provided with 85 means for limiting the action of said bolts, whereby the said two sections are fixed relatively to each other, substantially as set forth.

3. In a bending-machine, a roll consisting 90 of the combination with two elemental roll-sections, of a shaft adapted to mount said roll at its end, said shaft provided with a shoulder adapted to limit one of said sections in its motion in the direction of the axis of the shaft, the other section provided with 95 means adapted to vary the distance between said two sections, said shaft provided with means for limiting the action of said varying means, whereby said two sections are fixed 100 relatively to each other, substantially as set forth.

4. A roll consisting of the combination with two elemental roll-sections, of a shaft formed with a shoulder and provided at its end with a nut and washer, said roll-sections being 105 located between said shoulder and washer, and provided with means adapted to separate said sections, whereby they are caused to bear respectively against said shoulder and washer, whereby they are relatively fixed, 110 substantially as set forth.

5. A roll consisting of the combination of roll-section a , roll-section a' , shaft J provided with a shoulder j and formed with a threaded portion at its end, washer K , nut I and means 115 for separating said sections, whereby they are caused to bear respectively against said shoulder and washer and whereby they are relatively fixed, substantially as set forth.

6. A roll consisting of the combination of 120 roll-sections a and a' , shaft J provided with a shoulder j and a threaded end, a washer K , nut I , and screw-bolts M , substantially as set forth.

7. A roll consisting of the combination of 125 roll-sections a and a' , shaft J provided with a shoulder j and a threaded end, a washer K , a nut I , screw-bolts M and a washer N , substantially as set forth.

8. In a guide for guiding stock issuing from 130 rolls, the combination with a guide-rod laterally adjustable, a guide-body rigidly attached

to said rod, of a rotatable disk pivoted upon said guide-body, the face of the guide-body and inner face of the rotatable disk being provided with ball-races, and balls adapted 5 to bear in said races and having contact with said rotatable disk and guide-body, substantially as set forth.

In testimony that I claim the foregoing to be my invention I have hereunto set my hand this 14th day of May, A. D. 1896.

J. F. DOOLITTLE.
